Atty

Patented Aug. 17, 1926.

UNITED STATES PATENT OFFICE.

FRANCIS KARR, OF HOLLAND, MICHIGAN.

SPRING CUSHION.

Application filed December 26, 1922, Serial No. 608,899. Renewed January 23, 1926.

This invention relates to spring cushions of the type including a plurality of coil springs such as employed for seats, mattresses and the like, and it has for its principal object to provide improved means for connecting the several coils whereby the assembling of the coils is facilitated and the security of the joints is increased.

A further object of the invention is to provide means for maintaining the sections of the mattress in spaced relation.

Further objects of the invention will become apparent as the description is read in connection with the accompanying drawings, in which,—

Fig. 1 is a plan view of a spring assembly suitable for use in a mattress, a cushion or the like, with the intermediate portions broken away to indicate that any suitable number of coil springs may be used;

Fig. 2 is a side elevation of the assembly shown in Fig. 1;

Figs. 3 and 4 are plan views of right and left hand coils respectively;

Fig. 5 is an elevation of a detail showing the joint between certain of the coils and the wires for binding the margins of the assembly;

Fig. 6 is a fragmentary end elevation looking from the right at Fig. 1;

Figs. 7 and 8 are modified forms, showing the connecting spirals and the spacing springs made integral; and

Fig. 9 is a detail showing how the spacing springs may be interlocked with the connecting spirals.

The assembly shown in Figs. 1 and 2 includes a plurality of left hand coil springs 10, and right hand coil springs 11, connected by the helical springs 12, which enclose aligned portions of the surface coils of the springs, the marginal edges being bound by the wires or straps 13, threaded through the outside helical springs 12, and having their ends secured to the terminal springs as indicated at 14 (Figs. 1 and 5). When this assembly is used as a section of a mattress or the like, the spacing springs 15, here shown as helices, are used. They extend from the upper right hand to the lower left hand of each spring at the right hand end of the assembly (Figs. 1 and 5) and from the upper left to the lower right of each terminal spring at the left end of the assembly shown in Fig. 1.

The surface turns of each of the coils are provided with aligned portions having shoulders that cooperate with convolutions of the helical connecting springs to make secure joints between these springs and the surface coils throughout the assembly. Referring particularly to Fig. 3, the upper surface coil terminates in a substantially straight portion 16, aligned with a similar portion 17, but spaced therefrom by an intermediate offset portion 18. The off-set portion 18 is connected to the aligned portions 16 and 17 by integral parts 19 and 20, of the spring, which form shoulders for engagement with the convolutions of the connecting helices. The portion 17 joins a transversely extending portion 21 whereby another shoulder 22, in substantial alignment with the shoulders 19 and 20, is formed. The portion 21 joins a diagonally extending portion 23 which is connected by a lateral bend 24, to a portion 25, aligned with a similar portion 26, and spaced therefrom by an intermediate off-set 27, whereby additional shoulders 28 and 29, are formed. The lower surface coil includes similar aligned portions and shoulders arranged in just the reverse order, and to prevent confusion, they will be referred to only in a general way and without applying reference characters to each shoulder and portion.

Referring to Fig. 4, it will be seen that the upper and lower surface turns 30 and 31, of the left hand coil, are provided with similar aligned portions and shoulders arranged in like manner.

Referring again to Fig. 1, it will be seen that the off-set portions 18 and 27, lie outside of the connecting helices 12, whereas the aligned portions 16, 17, 25 and 26 are enclosed within the helices and thus the shoulders 19, 20, 22, 24, 28 and 29 are placed either in engagement with convolutions of the helices or in position to engage convolutions upon a very slight movement. It will therefore, be apparent that the connecting helices and the surface turns of the springs are securely joined and that the intermediate helices will securely bind the surface turns on adjacent sides of each pair of coils together.

The connecting helices and the spacing springs may be made of such proportions as to be easily threaded over the enclosed portions by which the assembly is facilitated.

The substantially right angle bends forming the shoulders 22, facilitate the building of the corners of the assembly.

Figs. 7 and 8 are inserted to illustrate 5 how the connecting helixes and the spacing springs may be made in one piece. When thus made, the portions corresponding to the connecting helixes 12, will be threaded through farther than final position and then 10 reversed to connect the end portions 32 and 33 into the next adjacent connecting 15 spring 12.

The intermediate portions of the spacing 20 springs may be closely coiled as indicated 15 at 34 (Fig. 9) to present a smoother surface to the covering of the cushion and prevent wear. The ends 35 and 36 however, have their convolutions spaced widely to accommodate the ends of the connecting 25 springs 12.

I claim as my invention:—

1. A spring cushion comprising a plurality of rows of upright springs, the surface turns of each spring in each row, at 25 each side, having aligned portions extending in the general direction of the alignment and provided between their ends with lateral projections, and continuous helical springs, each enclosing a part of the aligned 30 portions at the adjacent edges of two rows of springs and having convolutions arranged to cooperate with said lateral projections.

2. A spring cushion comprising a plurality of rows of upright springs, corresponding surface turns of the springs of 35 each row having aligned portions extending lengthwise to the row and spaced by an off-set intermediate connecting portion, and a helical spring enclosing said aligned 40 portions and having convolutions alongside said intermediate connecting portions.

3. A spring cushion comprising a row of upright springs, the terminal coil at one 45 end of each spring having a substantially right-angled bend in the plane of said terminal coil, and a pair of spaced aligned portions and a relatively off-set intermediate connecting portion beyond the bend, and a continuous helical spring enclosing both of

said aligned portions of the terminal coils 50 of all of said springs and extending upon the outside of the said intermediate connecting portions thereof.

4. A spring cushion comprising, in combination, a row of upright coil springs, the 55 terminal coils of the springs at one end thereof having aligned portions throughout the row, a continuous helical spring enclosing the aligned portions of the several 60 springs and a flexible tie extending through the bore of the said continuous helical spring and having its opposite ends anchored upon the terminal coils of the coil springs at the ends of the row.

5. A spring cushion including a row of 65 upright springs, means for securing the springs together, and a spacer spring for each end spring extending from one side of the upper turn to the opposite side of the lower turn.

6. A spring cushion including a row of 70 upright springs of which the end springs of each have surface turns provided with aligned portions spaced by off-set portions and a helical spring for each end upright 75 spring enclosing said aligned portions and extending from one side of the upper turn to the opposite side of the lower turn.

7. A spring cushion comprising a plurality of rows of upright springs, the surface turns of each spring in each row having, at each side, aligned portions and a helical spring enclosing the aligned portions on the adjacent sides of two rows, said aligned portions extending generally in the 80 direction of the alignment and embodying a bend for cooperating with several convolutions of the helical spring to prevent disengagement.

8. A spring cushion comprising a plurality of rows of upright springs, corresponding surface turns of the springs of each row having aligned serpentine portions including a plurality of reverse bends, and a helical spring enclosing parts of said serpentine portions and interlocking with other parts thereof.

FRANCIS KARR.
